UNITED STATES PATENT OFFICE.

EDWARD E. BAKER, OF MORGANTOWN, WEST VIRGINIA.

FILE-BOX FOR DOCUMENTS.

SPECIFICATION forming part of Letters Patent No. 339,254, dated April 6, 1886.

Application filed November 30, 1885. Serial No. 184,367. (No model.)

To all whom it may concern:

Be it known that I, EDWARD E. BAKER, a citizen of the United States, residing at Morgantown, in the county of Monongalia and State of West Virginia, have invented a new and useful File-Box for Documents, &c., of which the following is a specification.

The object of my invention is to provide an improved device for filing and holding documents in boxes or drawers, and one that is easily and quickly adjusted. I accomplish this object by the means illustrated in the accompanying drawings, in which—

Figure 1 is a front elevation of a cabinet with my file-box in position. Fig. 2 is a view in perspective of the file-box with documents in position. Fig. 3 is also a view in perspective of my file-box with compressor-board and bail drawn back. Fig. 4 is a view in perspective of the compressor-board and holding arm or lever.

The documents A are set on ends in the usual way against the upright stationary board B, which constitutes the front of the drawer. The lower end of the board B is connected to the base-board C of the drawer, and both pieces are sustained by the curved arm D and the angle-irons E. An angle-iron or strap, F, is connected to both edges of the movable compressor-board, and extends around the curved arms, and is bent or twisted at such angles that when the board is in a vertical position against the documents on file, a metal brace or bail, G, is carried up along with the compressor or binding board, and when in position rests upon the curved arms, and serves to draw the lower outer corners of the bent straps against the under faces of the curved arms and hold the compressor-board in position against the documents. When drawn backward the compressor-board will assume an inclined position, as shown in Fig. 3, with the upper angles of the straps resting upon the curved arms.

At the angle shown in Fig. 3 the inner face of the compressor-board is always in position to receive documents thrown backward in searching for headings or indorsements, and can be easily compressed or forced upward against the documents without binding of the curved straps upon the curved arms.

A bail, G, is pivoted to the compressor or binding board, the ends of the arms entering the edges of the board near the upper ends of the straps in such a manner that the board will fall inside of the curved arms G' when it is moved backward or inclined, and the long arm G² will rest upon the arms of file-box and form a proper support for the binding-board at the angle of inclination shown in Fig. 3, and when the documents are in a vertical position and the binding-board is pressed against them, as shown in Fig. 2, the bail will drop down upon the curved arms of the box, and the long arm form a prop as well as a lock for the compressor or binding board and keep the documents pressed together in a vertical position. The bail also forms a convenient handle, by which the compressor-board can be drawn backward along the ways or curved arms of the box. As a substitute for the bail, however, the lever-arm H may be employed. It is pivoted to the front face of the compressor-board, as shown, and when in position the lower end drops down upon the face of the base-board of the drawer or file-box, and acts as a brace or stop to prevent the compressor or binding board from springing backward when the latter is forced up against the document.

By placing the thumb against the curved lip H' of the lever and pressing against that point the lower end of the lever-arm will spring backward and upward away from the base-board, when the compressor-board can be moved along the curved ways or arms at any desired point. By this means the papers can be easily referred to, and an inclined rest or support provided while making search for any particular document, and the compressing attachment be quickly replaced without binding of the mechanism or parts.

Having thus described my invention, what I claim, and desire to secure by Letters Patent, is—

1. In a file-box for documents, the combination, with the board B and curved arms D D, of the movable compressor-board provided with straps F, which inclose the arms D D, the inclosing portion of said straps being so inclined or bent that when the compressor is in a vertical position the inner opposite edges of said

portions will be in contact with the arms, and when the compressor is thrown back into an inclined position the parallel sides of said portions will be in contact with the arms, substantially as shown and described.

2. The combination of sides B and C, the curved arms D D, the movable compressor-board, the inclined inclosing-strap F, whose opposite edges touch the arms when the compressor is vertical, and whose parallel sides

uphold the compressor when thrown back, and the handle G, which forms a lock and support for the binding-board, substantially as shown and described.

In testimony that I claim the foregoing I 15 have hereunto set my hand and seal.

EDWARD E. BAKER. [L. S.]
